UNITED STATES PATENT OFFICE.

EDWARD J. WOODBURY AND JOHN LE VQUE, OF ROCHESTER, NEW YORK.

DEVICE FOR KEEPING TOBACCO MOIST.

SPECIFICATION forming part of Letters Patent No. 268,588, dated December 5, 1882.

Application filed September 18, 1882. (No model.)

To all whom it may concern:

Be it known that we, EDWARD J. WOODBURY and JOHN LE VQUE, both of Rochester, in the county of Monroe and State of New 5 York, have invented a new and useful Improvement in Devices for Keeping Tobacco Moist, which improvement is fully set forth in the following specification and accompanying drawings.

10 Manufactured tobacco, known to the trade as "fine-cut tobacco," possesses a certain amount of moisture or dampness when it leaves the hands of the manufacturer, which dampness is an essential condition of the tobacco when prepared for consumers' use. While such tobacco is kept standing in suitable receptacles in retail stores—such as jars, pails, or other vessels—the moisture is gradually reduced by the process of natural evaporation, and if not continually 15 supplied leaves the tobacco dry and "chaffy," being thereby rendered unfit for sale and use. To preserve or continue this damp or moist state of the tobacco in the receptacle while being retailed therefrom is the object of our invention, 20 and we effect this by forming a hole in the top or cover of the receptacle, and insert therein a perforated cup or bowl designed to contain a substance or body—such, for instance, as a sponge saturated with water or other diluted 25 liquid—which bowl or cup extends to some distance below the cover of the receptacle and into the surrounding tobacco, means being employed to prevent any water escaping into the tobacco.

30 Referring to the drawings, Figure 1 is a vertical central section of the bowl with its cover and a portion of the cover of the pail or vessel holding the tobacco, and Fig. 2 a view looking down on top of the bowl.

35 B is the top or cover of the vessel holding the tobacco, and D a bowl set into an opening, d, through said cover and reaching down into the tobacco, the said bowl resting, by means of a shoulder, a, upon the cover B. The bowl is 40 fitted with a tight cover, F, as shown, to prevent the escape of vapor from within said bowl out at the top thereof; and said bowl is further provided with numerous perforations b through its shell, below the cover B of the tobacco-pail. The bowl is intended to receive a 45 sponge, wad of cotton, or other suitable ab-

sorbent for water, well saturated, the vapor from which, passing through the openings b, communicates moisture to the tobacco to supply the waste of moisture due to natural evaporation, above mentioned, and keeps the tobacco in a desired state of dampness. The perforations b are purposely made at the sides of the bowl, as shown, and not at the bottom thereof, so there may be a close receptacle or basin at 55 c to catch and hold the drippings from the sponge should the latter at any time be oversaturated, and the water lodging at c at any time acts as a reserve to be reabsorbed by the sponge as the latter becomes dried from evaporation. The perforations b are made through the shell, so as to incline downward from without, as shown, so that any water that may be pressed from the sponge in them will flow inward to the basin c, and not drain into the tobacco. 60

The bowl, not being fastened to the cover B of the pail, may be readily transferred from one pail to another, so that as one pail is emptied said bowl may be inserted in the cover of 75 another filled with tobacco. If the tobacco becomes too moist, the cover F may be partially removed from the bowl and allow the water to evaporate outward at the top.

By the use of this device the sponge may be 80 removed and cleansed at any time, or resaturated and replaced within the bowl by merely removing the cover F, and without opening the tobacco-pail; and the bowl may at any time be 85 removed for the purpose of washing, and replaced without loosening any screws or other fastenings, or opening the pail by removing the cover thereof.

It is found that in using the devices heretofore produced for keeping the tobacco moist 90 water is liable to drip directly into the tobacco, or be splashed over into the same should the pail be moved from one place to another, or otherwise disturbed, which water received into the tobacco causes it to mold and become destroyed. 95 In using the device herein described, on account of the mouth G of the bowl being outside of the cover of the pail, and the perforations b being inclined downward and inward, as set forth and shown, no water can drop or be 100 splashed into the tobacco from the bowl, only the vapor of the water passing through said

perforations coming in contact with the tobacco, as above stated; and this device is very cheaply produced.

This device may be employed to keep other articles besides tobacco moist, which require to be kept in a state of dampness.

What we claim as our invention is—

1. In combination, the cover B of a receptacle for holding tobacco, provided with an opening, d, through the same, and the perforated bowl D, inserted in said opening and made removable therefrom, and resting upon the cover B by means of a shoulder, a, said bowl being provided with a tight cover, F, substantially as shown and specified.

2. In combination with the cover B of a receptacle for holding tobacco, provided with an opening, d, through the same, the perforated

bowl D, inserted in said opening d and resting upon the cover B by means of a shoulder, a, said bowl being provided with a tight cover, F, and basin c, substantially as and for the purpose specified.

3. In combination with the cover B, the bowl D, placed in an opening, d, in said cover, and provided with perforations b through its side, below the cover B, said openings being inclined downward and inward, and said bowl being provided with a basin, c, substantially as shown and described.

EDWARD J. WOODBURY.
JOHN LE VQUE.
